MAGNETIC TAPE DUPLICATOR CONSOLE

Benjamin N. Yamada, Sunnyvale, Calif., assignor to
Consolidated Video Systems, Inc., Santa Clara, Calif.

Filed Apr. 24, 1972, Ser. No. 247,262

Term of patent 14 years

Int. Cl. D14—01; D14—02
U.S. Cl. D26—14 B

FIG. 1

FIG. 3

FIG. 2

FIG. 4

FIG. 5

FIG. 6

FIG. 1 is a perspective view of a magnetic tape duplicator console embodying my new design.

FIG. 2 is a plan view of the control panel portion thereof.

FIG. 3 is a front elevational view thereof.

FIG. 4 is a side elevational view thereof.

FIG. 5 is a rear elevational view thereof.

FIG. 6 is a bottom plan view thereof.

I claim:

The design for a magnetic tape duplicator console, as shown.
